UNITED STATES PATENT OFFICE.

FREDERICK A. HART, OF NEWARK, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,370,312.

Specification of Letters Patent.

Patented Mar. 1, 1921.

Application filed January 14, 1916. Serial No. 72,015.

To all whom it may concern:

Be it known that I, FREDERICK A. HART, a citizen of the United States, residing in Newark, in the county of Essex and State 5 of New Jersey, have invented certain new and useful Improvements in Combined Typewriting and Computing Machines, of which the following is a specification.

My invention relates to computing machines, and is herein disclosed as applied to an Underwood-Hanson combined typewriting and computing machine in which the numeral keys of the typewriter set up numbers on computation members, and these 15 numbers are later carried into computing or adding wheels.

My invention is designed to be used with computing machines in which there are several adding heads or totalizers, and therefore I have herein shown it as applied to 20 an Underwood-Hanson machine having two gangs of computing wheels. Such combined typewriting and computing machines are often used for doing either several varieties 25 of work, or else work which requires totalizers to be in use in some writing zones at one time and in other zones at another time. It has been found, however, that in the hands of the ordinary operative or typist, the separate settings of the connections to the different totalizers are troublesome, because they involve the setting of unfamiliar types of parts to control unfamiliar mechanical combinations, and therefore, the setting of 35 such parts is disconcerting to the average person into whose hands such machine is likely to be placed for use.

In some combined typewriting and computing machines the zones of computation 40 are selected either by denomination selectors directly, or by devices controlling such denomination selectors. I have found it advantageous to provide a handle or finger-piece of a familiar type which the operative 45 of such a combined typewriting and computing machine may adjust in any one of several positions, with the result that in one position the finger-piece will make certain denomination selectors effective or ineffective and in another position may be effective in an entirely different manner, so that either the same denomination selectors, or some of them, may be made effective where they were ineffective before, and vice

versa, or other selectors may be made effective or ineffective.

I have disclosed this invention, as intimated above, on a combined typewriting and computing machine of the Underwood-Hanson type, such as is shown in my prior 60 application, Serial No. 466,836, filed December 10, 1908 (now Patent No. 1,270,411, of June 25, 1918), and in this machine I have found it simplest to effect the silencing by setting the denomination selectors themselves at ineffective positions.

Other features and advantages will hereinafter appear.

In the accompanying drawings,

Figure 1 is a sectional side view, largely 70 diagrammatic of an Underwood-Hanson combined typewriting and computing machine, showing my invention as applied thereto.

Fig. 2 is a detail of the denomination- 75 selector controlling handle.

Fig. 3 illustrates a detent for holding said handle positioned.

Fig. 4 is a perspective view, showing some 80 parts of the typewriter carriage, and some adjacent parts, to illustrate the relationship of my invention to said parts.

Fig. 5 is a sectional front view, showing parts arranged much as in Fig. 4.

Fig. 6 is a plan view of five denomination 85 selectors on a typewriter carriage, two of which are those shown in Fig. 4, but with the controlling handle differently adjusted.

Fig. 7 is a view similar to Fig. 6, with 90 the parts differently adjusted, and only two denomination selectors being shown.

Fig. 8 is an enlarged detail view of one of the connections to the operating rods.

In the usual Underwood-Hanson com- 95 bined typewriting and computing machine, alphabet keys 1 and numeral keys 2, depress key-levers 3, so that sub-levers 4 connected thereto swing type-bars 5 upwardly and rearwardly, with the result that types 100 6 on said type-bars print against the front face of a platen 7, said platen forming part of the usual traveling carriage 8. Whenever any alphabet key 1 or numeral key 2 is depressed, the actuated type-bar 5 strikes 105 a segmental universal bar 9, causing said universal bar to vibrate the usual typewriter feeding dogs 10, said dogs permitting

the carriage 8 to be drawn along a step at a time at every key stroke in the usual manner, said dogs accomplishing this by their alternate engagement with the escape-
5 ment wheel 11 which is connected to the usual pinion 12, meshing with the usual rack bar 13, said rack bar being connected to the typewriter carriage. The carriage is drawn along in this manner, because it is
10 constantly under tension of the usual spring barrel (not shown herein).

Whenever a numeral key 2 is depressed within the computing zone, it not only feeds the carriage 8 along a step, but it also sets 15 up on a computation bar the digit which is being printed at the moment, and after all the digits of a number have been so set up, the digits are carried into a register comprising computing or adding wheels 14
20 in the usual manner. To bring about this setting up of digits, the typewriter carriage is provided with a denomination selector 15 in the form of a pivoted lever or camming tappet, which is adapted to ride *seriatim* 25 under a series of jacks 16 in a casing forming a head, as the typewriter travels along, and cause said jacks to raise pin-bearing computation members 17 within the range of pin-setting bars 18, one of which 30 is actuated every time its numeral key 2 is depressed. The pin-bearing bars 17 normally hold their pins 19 beneath and out of range of the pin-setting bars 18, but whenever the typewriter carriage enters a 35 computing zone, the dog or tappet 15 rides under a jack 16 and causes that jack, by means of the usual connections, to raise its pin-bar 17 so that the pins 19 thereon will be within range of the pin-setting bars 18.
40 If a numeral key is depressed in the adding zone, its pin-setting bar 18 swings downwardly and depresses its pin 19 on the bar 17 which is at the moment raised by the dog 15, with the result that the depressed pin 45 projects its lower end beneath the pin bar 17. As the typewriter key rises, the typewriter carriage feeds along one space, dropping the pin bar 17 on which the pin has just been set, and raises another pin bar to 50 the pin-setting level, a key depression again setting a pin, and so on.

When the series of pins have thus been set up, representing all the digits of a number, the number represented by them is carried 55 into the computing wheels 14 by means of a general operator, which includes a cross bar 20 and side bars 21. The cross bar 20 of the general operator drives the bars 17 by means of the projecting ends of the depressed pins, with the result that each pin bar is driven to an extent depending on the location of the pin depressed, and each pin bar 60 turns its computing wheel 14 by means of a rack 22 formed on the front end of the 65 pin bar, said rack constantly engaging a

pinion 23 which is connected in the usual manner by means of a pawl-and-ratchet to its computing wheel 14. The general operator may be actuated by the usual segment 24 and idle pinion 25.

70

On its return stroke the general operator brings back the pin bars 17 to their normal position, so that the pins 19 stand beneath their setting bars 18, and at the very end of the return stroke all of the depressed pins 75 are restored by means of the usual pin-restoring plate 25^a.

75

The connections between the jacks 16 and the pin bars 17 include the usual wires 26, which extend downwardly behind the pivot 80 rod 27 on which the jacks 16 are journaled, said wires engaging the rear ends of bell-crank 27^a, said bell-cranks at their forward ends engaging the usual linkages 28, forming a transposition device, so that each jack 85 16 operates only its own pin bar 17.

If it is desired to subtract, the operative may press a subtraction handle 29 to thrust rearwardly the usual subtraction bar 30, thus altering the connections in such a way 90 that the mechanism will perform complementary subtraction in the manner set forth in the co-pending application, Serial No. 626,550, filed May 11, 1911, (now Patent No. 1,278,812, dated September 10, 1918.) 95 The method by which subtraction is done forms no part of the present invention, and will not therefore be described in any further detail. It may be noted, however, that to avoid confusing the typist all the active 100 registers add when any adds, and the active ones subtract when any subtracts.

The said machine is herein illustrated as adapted to either add or subtract in any one of several columns, and is further illustrated 105 as adapted to have the computing devices selectively silenced in any column. The machine, in addition, is provided with the usual silencing rolls 32, each of which is adapted to support the tappets 15, when adjacent the 110 jacks 16, said tappets being normally beneath and clear of the jacks 16. This may be accomplished in the usual manner by mounting the tappets on blocks 33 which are pivoted on the usual rod 34, reduced at 115 its end 34^a, to allow insertion and removal of blocks 33, and the blocks 33 are provided with the usual teeth 35 for engaging the usual rack bar 36.

In the normal operation of the machine, 120 each block 33 is normally dropped down, so that its body rests on the rod 36, thus holding its tappet 15 clear of the jacks and therefore ineffective. In the adding zone, however, each block rides up on the silencing 125 roll 32, and holds its tappet 15, so that its path will carry it across the jacks 16 and raise them *seriatim*. Either roll 32, however, may be manually silenced by means of its usual handle 37, one of which is pro- 130

vided on each side near the front of the machine, and is connected by means of a link 38 to a long bell-crank 39, said bell-crank having an arm 40 which is adapted to rock the silencing roll 32 outward to a position clear of the blocks 33, said arm 40 accomplishing this by means of a rock arm 41 fast on the shaft 42, which carries the silencing roll 32, said roll being pivoted in arms 43 fast on said shaft. The handle 37 may be latched so as to hold the roll 32 outward by catching the handle in an L 44 of an elongated slot 45.

Ordinarily there are only one or two handles 37, which respectively control either of the silencing rolls 32, or else each of which controls half the silencing rolls 32, if the machine has more than two registers. In order to provide means for selectively silencing the tappets 15, I have provided an auxiliary silencing means adapted to selectively be effective on the tappets 15, even when the tappets are held in upward effective position by the silencing rolls 32. For this purpose, the tappets 15, as best shown in Fig. 5, are pivoted in the usual manner on their blocks 33 by means of pivots 46 in the blocks 33. The tappets 15 are so shaped that while they are able to swing freely during the return movement of the carriage, they are held in upright position during the forward traveling movement thereof. For this purpose each tappet 15 is provided with the usual flat face 47, which, during the traveling movement of the carriage, lies flat against a wall 48 of its block 33, the tappet 15 being normally held in such position by means of a light spring 49. During the return movement of the typewriter carriage, however, the tappet can swing freely to ride over the jacks, because there is no wall of the block 33 to prevent it from swinging out practically horizontal, and because its spring 49 is very light.

In order to selectively make the tappets 15 ineffective, I have found it possible to provide a separate silencing member or lever for any desired tappet 15 which is adapted to rock its tappet over into its horizontal position, and thereby hold it free from the jacks with which it would normally engage during its traveling movement. These levers, as seen in Fig. 4, may be of two forms, one of which is shown at 50, adjacent the head of jacks marked "No. 3," and said lever is pivoted intermediate its ends near the rear end of the block 33, and is provided with a tail 51, which has a pin-and-slot connection 51 with a radial pin 52, projecting from a manually controlled adjusting rod 53. The pin 52 is mounted on a collar 75 which is secured to the rod 53 by a set screw 76. It will be obvious that by shifting the rod 53, the lever 50 may either be entirely ineffective, or may be swung over

its tappet 15, in such a way as to swing said tappet downward to the left, and hold it clear of the jacks in the head "No. 3." In this way the silencing of said tappet is entirely independent of the silencing roll 32 for that head, and if said silencing roll is always effective, the tappet 15 shown at jack-head "No. 3" may be individually controlled in any manner the operative may prefer.

At the jack-head "No. 1" is shown a tappet 15, which is under the control of a silencing lever 54, of a somewhat different type, said lever 54 being pivoted on its block 33 toward the rear end of said block, and being short compared with the lever 50. (In the present machine, register and jack-head "No. 2" are omitted.) This lever 54 is controlled by the rod 53 by means of a pin-and-slot connection 55, similar to the pin-and-slot connection 51, but is controlled indirectly by said connection, this being so because said connection 55 is effective on an intermediate lever 56, having said pin-and-slot connection at one end thereof, and engaging the lever 54 at the opposite end.—it being pivoted intermediate these points. The result is that if the rod 53 is set at the extreme right-hand position, which is illustrated in Fig. 4, the tappet 15 adjacent the jack-head "No. 3" will be silenced, while the tappet 15 adjacent the jack-head "No. 1" will have its lever 54 thrown to the farthest point possible from its effective point. If the rod 53 is thrown to the left-hand limit of its throw, the lever 50 will be thrown to ineffective position, whereas the lever 54 will be made effective to silence its tappet 15. This last-named condition is illustrated in Fig. 7.

If the rod 53 is set at an intermediate position, both the levers 50 and 54 are ineffective, and both of the tappets 15, seen in Figs. 4 and 7, will be effective. Such a condition is shown in Fig. 6.

The rod 53 is provided with a handle 57 for convenience in adjusting it, and with an indicator 58 which plays over a scale 59, and indicates to the operative exactly what jack-heads, and therefore what registers are selectively effective and ineffective. In the present embodiment the rod 53 is shown as controlling only two adding heads, this being found sufficient for certain bookkeeping needs, and the scale illustrated, therefore, is provided with digits "1" and "3," which are adapted to indicate, by the pointer 58, whether the tappet associated with register or jack-head "1" or that associated with "3" is effective, the effective tappet being the one on which the selecting device is ineffective. Intermediate this scale is the letter "N" to indicate that the selecting device is effective on neither of the tappets. The rod 53 is slidably mounted in extensions 130

60 of the usual brackets 61 of the typewriter carriage, and is provided with three sockets 62 which are adapted to coöperate with a dentent pin 63 projecting from a spring 64 through an opening in one of the bracket extensions 60. It will be understood that the dentent device, just described, has the additional function of assisting in placing rod 53 in proper adjusted positions. In other words, the dentent pin 63 in connection with the sockets 62 insures uniform positioning of rod 53 in its three different positions for adjustment. The pin-and-slot joints 51 and 55 are allowed sufficient play to enable the blocks 33 to have all the freedom of vertical movement they require.

The adjusting rod 53 is provided with a collar 65 to limit its outward throw, so that it will not escape from the brackets in which it is slidably mounted, and an enlarged hub 66 on the handle 57 limits the throw of said rod in the opposite direction.

The pins of the pin-and-slot connections 51 and 55 are mounted in collars 75, which for purposes of manufacture are advantageously adjustable along the rod 53, and are fastened by set screws 76 in their proper positions.

The tappets 15 may be made ineffective, if desired, individually, or any number of them, by swinging them up around the rod 34 on which their blocks 33 are pivoted. The pin-and-slot connections 51, 55 are so designed to permit this to be done perfectly freely.

The machine herein illustrated in Fig. 6 is adapted to do computing in three columns, on two registers, and, for this purpose, is provided with two sets of tappets 15, the tappets of each set being effective on only their own jack-head, and through it on their own register. For this purpose, the tappets 15 of one set, as shown at 67, 68 and 69, are all in a single plane, to be effective on jack-lugs 70 (see Fig. 4), which are set back from the ends of the jacks. The tappets 67, 68 and 69, therefore, as will be determined by an inspection of Figs. 4 and 6, will be effective only on jack-head "No. 1." The other tappets 71, 72 are effective on jack-head "No. 3," only, and, for this purpose are set in another plane well forward from the rear ends of the blocks 33, in which they are mounted, and all lie in the plane of lugs 74, which are at the extreme front of the ends of the jacks in jack-head "No. 3."

The tappets provided in Fig. 6 are adapted to be used in making out bills and statements according to the outline given below. This outline utilizes a kind of bill commonly used in commercial transactions, and is a kind of bill which cannot be made out on a machine having automatic shifts from addition to subtraction and vice versa, un-

less the automatic connections are extremely complicated.

The columns.

Charges.	Totals.	Balance.	
	Credits.		70
\$20.00			
\$10.00			
\$10.00			
	40.00		75
	5.00		
	5.00		
	5.00		
	15.00		80
		25.00	

In the column of charges there are entered items of \$20, \$10 and \$10. These items are added in both registers Nos. 1 and 3 by the tappets 67 and 71. Both registers then show a total of \$40. The typewriter carriage is then shifted along to the column or zone for totals. In this column, tappet 68 and therefore, its register (No. 1) are made ineffective by shifting the handle 57 to the Fig. 7 position, and the subtraction bar 30 made effective; then the total of \$40. is printed, thus subtracting it out from "No. 3" register by tappet 72, which remains effective. The typewriter carriage is again brought back to enter credits in this same total column, and the handle 57 remains at the same position, but the machine is now caused to add, and credit items of \$5, \$5 and \$5 are therefore entered and added in register "No. 3" by tappet 72, additively. The typewriter carriage is now brought back to write in its total and credit column again, and the sum of the credit items, amounting to \$15. is subtracted from both the registers; for this purpose the subtraction bar is made effective, and the handle 57 is shifted to its Fig. 6 position, so that both the tappets 72 and 68 are effective. The writing of the total credits will now erase said credits from the "No. 3" register and deduct said credits from the "No. 1" register, leaving the "No. 3" register at zero, ready for the next statement. "No. 1" register now shows a balance of \$25, which is the total balance to be written on this bill or statement to complete the making out of it. The typewriter carriage is therefore positioned at the balance column, which makes the tappet 69 effective on the "No. 1" register, and with the subtraction bar still effective, the \$25 is written in the balance column, thus erasing the \$25 from the "No. 1" register, leaving both registers at zero, and the statement or bill ready for removal from the machine.

The arrangement of registers and tappets shown in Fig. 4 is one adapted for many kinds of work, such as making out insurance

premium receipts, in which items are always entered in one of two columns on a great many forms, but never elsewhere, and of which it is desired to keep a separate total for each column. While the system of silencing rolls 32 and handles 37 may be used for such a purpose, it is found in practice that operatives cannot be trusted to remember to shift both handles each time, although experience shows that they will practically never make a mistake in using a device such as that shown in Fig. 4. The silencing rolls 32 therefore are usually used only for semi-permanent adjustments, such for example as for a day's work on a special form, when the machine is otherwise adjusted for more complicated forms.

Variations may be resorted to within the scope of the invention, and portions of the improvements may be used without others.

Having thus described my invention I claim:

1. In a computing machine, the combination with a unitary computing mechanism, of a plurality of registers for registering the numbers simultaneously or separately, a denomination selector for each register adapted to be set to effective or ineffective position, and a single finger-piece selectively settable when said selectors are at effective position, for making any of said selectors selectively ineffective at will.

2. In a computing machine, the combination with a unitary computing mechanism, of a plurality of registers for registering numbers, denomination-selecting means, including a denomination selector for each register adapted to be set to effective or ineffective position, and means, including a single finger-piece selectively settable when said selectors are at effective position, for making any of said selectors selectively ineffective at will, the position of said finger-piece indicating the relation between the same and the selectors.

3. In a computing machine, the combination with a plurality of simultaneously or separably operable registers, of a separate denomination selector for each of said registers, and a single finger-piece adjustable to selectively determine which ones of said selectors shall be effective.

4. In a computing machine, the combination with numeral keys and a plurality of sets of computing wheels, of a plurality of denomination selectors for the sets of wheels, and a single finger-piece for selectively making selected selectors ineffective.

5. In a combined typewriting and computing machine, the combination with a traveling carriage and a plurality of denomination selectors coöperating with said carriage, of a device associated with each selector for making it ineffective, and a single

finger-piece to adjust all of said devices so as to make said selectors selectively ineffective.

6. In a combined typewriting and computing machine, the combination with a traveling carriage and a plurality of denomination selectors coöperating therewith, of a plurality of registers selectively coöperating with said selectors, a separate device for each selector for making it ineffective, a single finger-piece for controlling said devices, and two different kinds of leverages for operating said devices by said finger-piece.

7. In a combined typewriting and computing machine, the combination with a traveling carriage and a plurality of denomination selectors coöperating with said carriage, of a plurality of registers selectively coöperating with said selectors, a device associated with each selector for making it ineffective, and a single finger-piece adjustable to make said selectors selectively ineffective.

8. In a combined typewriting and computing machine, adapted to subtract, the combination with a plurality of registers, all of which subtract or add when any subtracts or adds, of typewriter numeral keys controlling said registers, a denomination selector for each register, and a single finger-piece adjustable to make said selectors selectively effective on their registers, thereby determining whether said registers shall individually be idle or active during a computation.

9. In a combined typewriting and computing machine adapted to subtract, the combination with a plurality of registers, all of which subtract or add when any subtracts or adds, of typewriter numeral keys controlling said registers, a plurality of denomination selectors for each register, and a single finger-piece adjustable to make said selectors selectively effective on their registers, thereby determining whether said registers shall individually be idle or active during a computation.

10. In a combined typewriting and computing machine, the combination with a traveling carriage, of a plurality of denomination selectors mounted thereon, a separate block for each selector, on which it is mounted, a silencing lever for each selector, and means, including a single adjustable finger-piece, to manipulate said levers in opposite directions, the position of said finger-piece indicating the condition of said selectors.

11. In a combined typewriting and computing machine, the combination with denomination selectors pivoted thereon, of a silencing lever for each selector, a single finger-piece for adjusting said levers, and

pin-and-slot connections between said finger-piece and levers to permit said selectors to be swung independently of said finger-piece.

5 12. In a combined typewriting and computing machine, the combination with numeral keys and computing wheels, of pin bars controlled by said keys for determining how far said wheels shall be turned, a 10 traveling carriage, a finger-piece slideable on said traveling carriage, denomination selectors on said traveling carriage, reversely moving levers operated by said finger-piece, and members forming parts of said levers 15 for selectively making said denomination selectors ineffective.

13. In a combined typewriting and computing machine, the combination with numeral keys and computing wheels, of pin bars controlled by said keys for determining how far said wheels shall be turned, a traveling carriage, a finger-piece slideable on said traveling carriage, denomination selectors on said traveling carriage, reversely 20 moving levers operated by said finger-piece, and members forming parts of said levers for selectively making said denomination 25 selectors ineffective, the position of the finger-piece indicating the relation between the same and the selectors.

14. In a combined typewriting and computing machine, the combination with numeral keys and computing wheels, of pin bars controlled by said keys for determining how far said wheels shall be turned, a traveling carriage, a finger-piece slideable on said traveling carriage, denomination selectors on said traveling carriage, reversely moving levers operated by said finger-piece, 30 and members forming parts of said levers for selectively making said denomination 35 selectors ineffective, one of said levers engaging said finger-piece directly, the other of said levers engaging said finger-piece 40 through an intermediate lever, whereby said finger-piece moves one lever in one direction and the other lever in the opposite direction.

15. In a combined typewriting and computing machine, the combination with numeral keys and computing wheels, of pin bars controlled by said keys for determining how far said wheels shall be turned, a traveling carriage, a finger-piece slideable on said traveling carriage, denomination 50 selectors on said traveling carriage, reversely moving levers operated by said finger-piece, members forming parts of said levers for selectively making said denomination 55 selectors ineffective, blocks on which said selectors and said levers are mounted, and a rod on which said selectors are pivoted, said pivot rod permitting said selectors to be thrown upward to ineffective position 60 or downward to ineffective position.

16. In a combined typewriting and computing machine, the combination with numeral keys and computing wheels, of pin bars controlled by said keys for determining how far said wheels shall be turned, a 70 traveling carriage, a finger-piece slideable on said traveling carriage, denomination selectors on said traveling carriage, reversely moving levers operated by said finger-piece, members forming parts of said levers for 75 selectively making said denomination selectors ineffective, brackets forming parts of said typewriter carriage, and extensions on said brackets in which said finger-piece slides, one of said extensions comprising a 80 scale coöperating with said finger-piece.

17. In a combined typewriting and computing machine, the combination with numeral keys and computing wheels, of pin bars controlled by said keys for determining how far said wheels shall be turned, a 85 traveling carriage, a finger-piece slideable on said traveling carriage, denomination selectors on said traveling carriage, a pivot rod supporting said selectors, reversely moving levers operated by said finger-piece, members forming parts of said levers for 90 selectively making said denomination selectors ineffective, brackets forming parts of said typewriter carriage, extensions on 95 said brackets in which said finger-piece slides, one of said extensions comprising a scale coöperating with said finger-piece, a rack bar adapted to hold said denomination 100 selectors when in effective position, and connections whereby said selectors may be removed from their pivot rod.

18. In a combined typewriting and computing machine, the combination with numeral keys and computing wheels, of pin 105 bars controlled by said keys for determining how far said wheels shall be turned, a traveling carriage, a finger-piece slideable on said traveling carriage, denomination 110 selectors on said traveling carriage, reversely moving levers operated by said finger-piece, members forming parts of said levers for selectively making said denomination 115 selectors ineffective, and means for limiting the throw of said finger-piece.

19. The combination with a plurality of registers, of a series of jack-actions, one for each denomination in each register, a plurality of tappets of different ranges for operating successively the individual jack-actions for different groups corresponding to different registers, and a plurality of other tappets individually silenceable, so as to selectively operate said jack-actions to control the running-up of numbers into said 120 registers.

20. The combination with a register, of a series of jack-actions corresponding to the several denominations of said register, and a denominational selector to operate said jack- 125 130

actions successively, comprising a block, a tappet yieldingly mounted on said block so as on the return movement to pass idly by said jack-actions, and silencing means for 5 said tappet, causing recession of said tappet by a movement relative to said block to enable it to pass idly by said jack-actions in both directions.

21. The combination with a register, of 10 a series of jack-actions, one for each denomination of said register, a denominational selector for operating said jack-actions successively, including a block and a tappet adjustably mounted on said block, means for 15 controlling the ineffective and effective conditions of said selector by moving the same vertically, out of and into striking range of said jack-actions, and means for controlling the effectiveness of said selector by adjusting said tappet relatively to said block.

22. The combination with a plurality of registers, of a plurality of series of jack-actions, one for each register, and each series including a jack-action corresponding to 25 each denomination of the associated register, a denominational selector for each of said series of jack-actions, each of said selectors including a block and a tappet adjustably mounted on said block, between active and 30 inactive positions, and a unitary control acting on said tappets oppositely to render them effective and ineffective.

23. The combination with a plurality of registers, of a plurality of series of jack-actions, one for each register, each series including a jack-action for each denomination of the associated register, a plurality of denominational selectors having different ranges, so as to operate solely one series 40 of said jack-actions, and a unitary control simultaneously oppositely effective on said selectors, so as to render them silent and active to control the inaction and action of the corresponding registers.

24. In a computing machine, the combination with a plurality of registers, of actuating means therefor, comprising denomination-selecting means, including a denomination selector for each register, a single 50 controlling member, and means controlled by said member for selectively rendering said selectors ineffective.

25. The combination with a plurality of registers, of computing mechanism for actuating said registers, comprising a plurality of denominational members, a plurality of denomination selectors for controlling said denominational members, a controlling member, and means rendered effective by said controlling member to selectively render certain of said selectors ineffective, the position of said controlling member indicating the condition of said selectors.

26. In a computing machine, the combination with numeral keys and a plurality of sets of computing wheels, of numeral-key-controlled actuating means for said computing wheels, comprising denomination-selecting means including a plurality of denomination selectors through which said denomination-selecting means is actuated, and means including a single controlling member for selectively rendering certain of said selectors ineffective.

27. The combination with a traveling carriage and a plurality of denomination selectors mounted to travel therewith, of a device associated with each selector for making it ineffective, a single finger-piece, 80 means controlled by said single finger-piece to adjust said device so as to selectively make said selectors ineffective, and devices with which said selectors coöperate when in effective position.

28. The combination with a traveling carriage, of a plurality of denomination selectors mounted to travel therewith, a controlling member, and means controlled by said member to selectively render certain of 90 said selectors ineffective, the position of said controlling member indicating the condition of said selectors.

29. In a computing machine, the combination with numeral keys, of numeral-key-controlled computing means, comprising a plurality of sets of denominational members, a plurality of denomination selectors, means to effect a relative traveling movement between said denominational members and 100 said selectors to effect coöperation therebetween, devices associated with certain of said selectors for rendering them ineffective, a controlling member, and means actuated by said controlling member to selectively activate said devices to render certain of the corresponding selectors ineffective.

30. In a combined typewriting and computing machine, the combination with numeral keys and computing wheels, of computing-wheel-actuating means including a denominational member for each of said computing wheels, the extent of movement of said computing wheels being determined by the extent of movement of said denominational members, denominational-member-actuating means, numeral-key-controlled means to determine the extent of actuation of said denominational members, a traveling carriage, a controlling member movably 110 mounted on said carriage, denomination selectors mounted to travel with said carriage, and connections between said controlling member and certain of said selectors, whereby the position of said controlling member 120 will determine which of said selectors will be rendered ineffective, the position of said controlling member indicating the condition 125

of the selectors controlled by said connections.

31. A computing machine comprising a traveling carriage, a plurality of denomination 5 selectors mounted to travel therewith, a controlling member, settable to various positions, and means controlled by said member to selectively render said selectors ineffective, depending upon the position in 10 which said member is set.

32. In a machine of the character described, the combination with settable controlling elements thereof, and its tabulating paper carriage: of members adapted to be 15 brought into action upon said controlling elements through the tabulating shifts of said paper carriage, and means for collectively varying by one and the same act the co-operative relationships between said members and said elements to conform with differing requirements of the accounting work in hand.

33. In a typewriting and computing machine, the combination with a carriage, numeral-keys, a plurality of registers, indexing devices settable by the numeral-keys, and means to actuate the registers, of denomination-selecting mechanism for each register, each denomination-selecting mechanism comprising a selector and a set of 20 jack actions operable by the selector to co-operate with the indexing devices, and a device actuatable to render either one of the denomination-selecting mechanisms ineffective.

34. In a typewriting and computing machine, the combination with a carriage, numeral-keys, and a plurality of registers, each register comprising computing wheels 40 and pin-bars settable by the numeral-keys and to actuate the computing wheels, of denomination-selecting mechanism for each register, each denomination-selecting mechanism comprising a selector on the carriage 45 and a set of jack actions operable by the selector to move the pin-bars to pin-setting positions, a slide, and a finger-piece to operate said slide to render any one of the denomination-selecting mechanisms ineffective.

35. In a typewriting and computing machine, the combination with a carriage, numeral-keys, two registers, and indexing devices settable by the numeral-keys to control the computing, of denomination-selecting mechanism for each register, comprising a selector and a set of jack actions operable by the selector to co-operate with the indexing devices, a register-silencing device which 55 may occupy a neutral position, and means to move said device in either of two directions from its neutral position to render either register ineffective by silencing its denomination-selecting mechanism.

36. In a typewriting and computing ma-

chine, the combination with a carriage, numeral-keys, and a plurality of registers, each register comprising computing wheels, pin-bars settable by the numeral-keys and to actuate the computing wheels, of denomination-selecting mechanism for each register, each denomination-selecting mechanism comprising a selector on the carriage and a set of jack actions operable by the selector to move the pin-bars to pin-setting positions, a separate device associated with each denomination-selecting mechanism for making it ineffective, and a single element shiftable to selectively actuate said devices to selectively render any one of the registers 80 ineffective by making the associated denomination-selecting mechanism ineffective.

37. In a typewriting and computing machine, the combination with a carriage, numeral-keys, and a plurality of registers, each register comprising computing wheels and pin-bars, having index pins settable by the numeral-keys, for actuating the computing wheels, of denomination-selecting mechanism for each register, each denomination-selecting mechanism comprising a selector on the carriage and a set of jack actions operable by the selector to move the pin-bars to pin-setting positions, silencing means associated with the denomination-selecting mechanisms, and means to operate said silencing means to selectively render the registers ineffective.

38. In a typewriting and computing machine, the combination with a carriage, numeral-keys, and a plurality of registers, each register comprising computing wheels and pin-bars, having index pins settable by the numeral-keys, for actuating the computing wheels, of denomination-selecting mechanism for each register, each denomination-selecting mechanism comprising a selector on the carriage and a set of jack actions operable by the selector to move the pin-bars to pin-setting positions, co-operating means 100 comprising a common member and a plurality of cam-members thereon with which the selectors may engage while operating the jack actions of their respective registers, a finger-piece to determine the position of 115 said co-operating means, and a finger-piece to make any one of the denomination-selecting mechanisms ineffective to render the associated register ineffective when the co-operating means is effective.

39. In a typewriting and computing machine, the combination with a carriage, numeral-keys, and a plurality of registers, each register comprising computing wheels and pin-bars, having index pins settable by 125 the numeral-keys, for actuating the computing wheels, of denomination-selecting mechanism for each register, each denomination-selecting mechanism comprising a selector on the carriage and a set of jack actions op-

erable by the selector to move the pin-bars to pin-setting positions, coöperating means with which the selectors may engage while operating the jack actions of their respective 5 registers, a finger-piece to determine the effective or ineffective positions of said coöperating means, and a device to render any one of the registers ineffective by making the associated denomination-selecting mechanism ineffective when the coöperating means 10 is effective.

40. In a typewriting and computing machine, the combination with a carriage, numeral-keys, and a plurality of registers, 15 each register comprising computing wheels and pin-bars, having index pins settable by the numeral-keys, for actuating the computing wheels, of denomination-selecting mechanism for each register, said denomination-selecting mechanism comprising three devices, namely, a cam, a selector to be rendered effective by said cam and a set of jack actions associated with the pin-bars and to 20 be operated by said selector, and means common to all the registers to selectively render any one of said registers ineffective by making one of the three named devices of the associated denomination-selecting mechanism ineffective.

30 41. In a typewriting and computing machine, the combination with a carriage, numeral-keys, and a plurality of registers, each register comprising computing wheels and pin-bars, having index pins settable by the 35 numeral-keys, for actuating the computing wheels, of denomination-selecting mechanism for each register, said denomination-selecting mechanism comprising three devices, namely, a cam, a selector to be rendered effective by said cam and a set of jack 40 actions associated with the pin-bars and to

be operated by said selector, an element common to all the registers, and a finger-piece to operate said element to selectively render any one of the registers ineffective 45 by making one of the three named devices of the associated denomination-selecting mechanism ineffective.

42. In a typewriting and computing machine, the combination with a carriage, numeral-keys, and a plurality of registers, 50 each register comprising computing wheels and pin-bars, having index pins settable by the numeral-keys, for actuating the computing wheels, of denomination-selecting mechanism 55 for each register, each denomination-selecting mechanism comprising several devices coöperating with each other to move the pin-bars individually to their pin-setting positions, and means common to all the registers to selectively render any one of said registers ineffective by making one of the devices of the associated denomination-selecting mechanism ineffective.

43. In a typewriting and computing machine, the combination with a carriage, numeral-keys, and a plurality of registers, each register comprising computing wheels and pin-bars, having index pins settable by the numeral-keys, for actuating the computing wheels, of a train of connections for 70 each register comprising several elements to move the pin-bars to pin-setting positions, and means common to all the registers to selectively render the connections ineffective 75 by making one of the elements of the connection of the associated register ineffective.
